UNITED STATES PATENT OFFICE.

WILLIAM H. J. FITZGERALD, OF BRAINTREE, MASSACHUSETTS.

CUTTING DIE AND PROCESS OF MAKING THE SAME.

Application filed April 3, 1923. Serial No. 629,733.

To all whom it may concern:

Be it known that I, WILLIAM H. J. FITZGERALD, a citizen of the United States, and a resident of Braintree, county of Norfolk, 5 State of Massachusetts, have invented an Improvement in Cutting Dies and Processes of Making the Same, of which the following description, in connection with the accompanying drawing, is a specification, like characters on the drawing representing like parts.

This invention relates to improvements in cutting dies and processes for producing the same.

15 More particularly the invention relates to cutting dies such as are used for cutting leather and other materials into predetermined forms as for the soles and uppers of shoes, etc.

20 In the manufacture of shoes and like articles where different styles and sizes are made, a large number of different dies are required. Such cutting dies have heretofore been produced by forging strips of 25 steel to correspond to the form of a template or pattern and welding the ends of the strip together. This requires highly skilled labor and the production of such dies is very slow and expensive.

30 The object of the present invention is to provide a novel cutting die which may be formed of sheet metal of sufficient thinness to enable it to be bent to the desired form, but which is provided with a longitudinally 35 extending strengthening rib which will give to the die when formed sufficient rigidity to stand the strains to which it is subjected when in use.

40 A further object of the invention is to provide a die of the character specified formed of preferably rolled sheet metal of a quality which can be bent at ordinary temperatures, without the application of heat, and which will retain a permanent set 45 when bent to the desired form, the sheet or strip being provided with a preferably central longitudinally extending strengthening rib adapted to give to the sheet such rigidity as is required when the die is used in 50 the usual cutting machine.

55 A further object of the invention is to provide a die of the character specified in which the rib is recessed or notched in such a manner that it may be readily bent to the

required form and which will not impose 55 a lateral or torsional strain upon the body of the die by reason of the stretching or condensation of the metal along the curved or angularly bent portions of the die.

A further object of the invention is to 60 provide a novel means for securing the ends of a cutting die of the character above described.

A further object of the invention is to 65 provide a cutting die body of the character above described with a flexible cutting blade having its edge projecting beyond the edge of the body and its opposite edge preferably resting upon the shoulder formed by the longitudinally extending rib of the 70 body.

A further object of the invention is to 75 provide novel means for securing such a flexible cutting blade to the body of the die, so that the whole or a part may be replaced.

A further object of the invention is to 80 provide a novel process of forming a cutting die of the character above described.

Other objects and features of the invention will more fully appear from the following description and the accompanying drawing and will be particularly pointed out in the claims.

85 A die illustrative of a preferred embodiment of the invention is shown in the accompanying drawing, in which,

Fig. 1 is a plan view of a die for cutting uppers of shoes having a flexible cutting blade, viewed toward the edge of the blade;

90 Fig. 2 is a side elevation of the die illustrated in Fig. 1, viewed from the top, showing diagrammatically in dotted lines the beam of the cutting machine located at a distance above the die;

95 Fig. 3 is a detail view in perspective of a curved portion of the body formed of sheet metal, bent centrally upon itself to form a longitudinally extending rib and having a flexible cutting blade applied thereto;

100 Fig. 4 is a vertical transverse section of the die body and blade illustrated in Fig. 3, showing also a preferred clamping device for securing the blade to the body;

105 Fig. 5 is a plan view of a die of different pattern, embodying the invention, in which the body is formed from a rolled strip hav-

ing an integral, substantially central, longitudinally extending, rib and in which the body is provided with a cutting edge; and,

Fig. 6 is a transverse sectional view on line 6—6, Fig. 5.

The cutting die illustrated in the accompanying drawing comprises a strip 1, preferably of sheet metal, having a longitudinally extending, preferably centrally disposed, rib 2, the rib being provided with suitable recesses preferably in the form of V-shaped notches 3 located at suitable intervals along the curved portions of the die and similar notches 4 located at the angularly bent portions of the die. These V-shaped notches preferably extend through the rib with their apexes lying in the plane of the wall of the body.

In the construction of the die illustrated herein a straight strip of sheet metal having a longitudinally extending preferably central rib is measured off to the length required to extend around the periphery of the desired pattern. The slits or preferably V-shaped notches 3 are then formed in the rib 2 along the portions of the strip which are to conform to curved or angular portions of the pattern. The strip is then bent by the workman with a suitable tool to conform to the contour of the pattern, the V-shaped notches in the rib permitting such flexure of the sheet as is necessary to cause it to follow the contour of the pattern. The metal of the sheet should be of sufficient flexibility to enable it to be bent readily, preferably at ordinary temperatures, and of a quality which will have a permanent set when bent to the desired form.

By reason of the preferred V-shaped notches in the rib the body may be caused to conform either to an out-curve 5 in which case the outer edges of the notches will separate as the sheet is bent, or to an in-curve 6 in which case the outer edges of the notches will approach more closely together when the sheet is bent. Where the sheet is bent at substantially right angles the edges of the notches separate more widely as indicated at 4 in Fig. 1. When the sheet has been bent around the pattern the ends 7 and 8 are caused to abut and may be secured in abutting position by any suitable anchoring means.

One of the preferred means for securing the abutting ends of the body together consists in providing a block 9, preferably of greater thickness than the height of the rib 2, and provided with a longitudinally extending recess to embrace and preferably to fit upon the rib. The basal portion 10 of the block preferably lies flush with the base edge 11 of the body and the block desirably may be of sufficient length to provide an abutment to receive the blow from the die-actuating instrumentality.

The block 9 desirably is secured to the body between the rib and the basal edge 11 by rivets 12 or other suitable fastening means. Desirably one or more members 13 are connected to the body at opposite portions of the die to prevent spreading, collapsing, or other distortion of the die when in use.

While the body of the die thus formed may be provided with a cutting edge conforming to the pattern it is preferable to provide a removable and renewable cutting blade of relatively thin tempered steel. As illustrated in Fig. 1 a cutting blade 14 of thin flexible metal is bent around the body of the die to conform to the profiled surface of the body which corresponds to the pattern of the article to be cut. The edge 15 of this flexible blade projects at a distance beyond the edge 16 of the body. The opposite edge 17 of the cutting blade desirably rests upon or abuts against the shoulder formed by the rib 2 so that the cutting blade is rigidly backed up and prevented from yielding edgewise during the use of the die.

Suitable means are provided for securing the cutting blade to the body of the die. A preferred construction which is illustrated herein comprises a series of blocks 18 of the general character of the block 9 which is above described, for connecting the ends of the body together, the blocks 18 being provided with a suitable recess to embrace and preferably fit the rib 2 and with rivets or other fasteners 19 securing them to the body of the die. The blocks desirably are also provided with screws 20 having threaded engagement with the walls of apertures in the blocks and desirably are provided with angular recesses 21 to receive a tool for setting up and withdrawing the screws. The screws 20 are provided with flattened ends 22 adapted to engage the flat surface of the blade 14.

Preferably the blade 14 is provided with mitered ends 23 and 24, the upper overlapping end 24 being sharpened along its edge to insure the cutting of any material which enters between the adjacent ends of the blade as is more fully disclosed in my prior Patent Number 1,471,653 granted October 23, 1923.

Desirably the angularly bent portions of the die are provided with re-enforcing blocks 25 having recesses to embrace and preferably to fit the rib 2 and which also may be provided with clamping screws 20. These blocks may be provided with V-shaped notches 26 extending to the base of the groove so that the re-enforcing blocks 25 may be bent properly to fit around the abrupt corners of the die. These re-enforcing blocks and also other blocks 27, which may be termed hammer blocks, desirably are of considerable extent and have surfaces preferably

flush with the basal edge of the body to receive the stroke of the instrumentality which forces the die through the material to be cut. Such blow-receiving blocks may be 5 disposed at any desirable intervals along the die as will be readily understood by those skilled in the art.

The body of the die may be formed either of a strip of sheet metal having an integral, 10 longitudinally extending, rib, or of sheet metal folded longitudinally upon itself to provide a rib as illustrated in Figs. 3 and 4. In this construction the metal sheet 2, of which the body is formed, is bent upon itself to produce the rib 4. Strips of this kind may and have been produced by sheet metal working machines and no claim is, therefore, made to the particular form of 15 the strip apart from its use in connection with the manufacture of dies of the character above described.

In Figs. 5 and 6 another of the usual forms of dies for shoe uppers is illustrated. In this construction the die is shown as being 20 formed of a strip 28 of sheet metal having a substantially central, longitudinally extending, rib 29 formed integral with the sheet 28 preferably by rolling. This rib 29, like that heretofore described, is provided 25 with suitable notches 3 and 4 to permit the body to be bent into the desired form and the ends of the body are connected by means of a block 30 having a groove to receive and preferably fit the rib 29. In this construction the body is provided with a cutting 30 edge 31 instead of having a flexible cutter secured to the body, but it will be understood that even in this construction a suitable flexible cutter may be applied in the 35 manner heretofore described to conform to the manner heretofore described to conform to the contour of the pattern.

It will be understood that the embodiments of the invention disclosed herein are 40 illustrative in character and that various forms of cutting dies may be produced in accordance with the process disclosed herein.

Having thus described the invention, what is claimed as new, and desired to be secured by Letters Patent, is:

50 1. A cutting die comprising a body of thin metal bent to cause one of its walls to conform to the contour of the pattern to be cut, having an integral rib extending longitudinally of said body and recessed at the bent portions of said body to prevent lateral and torsional strains upon said body and means for securing the ends of said body together.

55 2. A cutting die comprising a body of thin metal bent to cause one of its walls to conform to the contour of the pattern to be cut, having an integral rib extending longitudinally of said body and recessed at the bent portions of said body to prevent lateral and torsional strains upon said body, means

for securing the ends of said body together and a tension member connecting oppositely disposed portions of said die acting to prevent expansion of the die when in use.

3. A cutting die comprising a body of thin metal bent to cause one of its walls to conform to the contour of the pattern to be cut, having an integral rib extending longitudinally of said body and recessed at the bent portions of said body to prevent lateral and torsional strains upon said body, means for securing the ends of said body together and hammer blocks secured to said body presenting surfaces to receive the blow of the die-actuating instrumentality. 75

4. A cutting die comprising a body of thin metal bent to cause one of its walls to conform to the contour of the pattern to be cut, having an integral rib extending longitudinally of said body and projecting substantially perpendicularly from the face of the contoured wall and recessed at the bent portions of said body to prevent lateral or torsional strains upon said body, means for securing the ends of the body together, 90 a thin flexible cutting blade fitting said contoured wall presenting a cutting edge projecting beyond the edge of said wall and having its opposite edge seated upon a shoulder formed by said rib and means for 95 securing said blade to said body.

5. A cutting die comprising a body of thin metal bent to cause one of its walls to conform to the contour of the pattern to be cut, having an integral rib extending longitudinally of said body and projecting substantially perpendicularly from the face of the contoured wall and recessed at the bent portions of said body to prevent lateral or torsional strains upon said body, means for securing the ends of the body together, a thin flexible cutting blade fitting said contoured wall presenting a cutting edge projecting beyond the edge of said wall and having its opposite edge seated upon a shoulder formed by said rib, and a plurality of members fastened to said body having adjustable means for clamping said blade against said body. 100 105

6. A cutting die comprising a body of thin metal bent to cause one of its walls to conform to the contour of the pattern to be cut, having an integral rib extending longitudinally of said body and projecting substantially perpendicularly from the face of the contoured wall and recessed at the bent portions of said body to prevent lateral or torsional strains upon said body, means for securing the ends of the body together, a thin flexible cutting blade fitting said contoured wall presenting a cutting edge projecting beyond the edge of said wall and having its opposite edge seated upon a shoulder formed by said rib, a plurality of blocks having recesses fitting said ribs, means securing said blocks to said body and adjustable clamping 110 115 120 125 130

In testimony whereof, I have signed my name to this specification. 125

WILLIAM H. J. FITZGERALD.
